UNITED STATES PATENT OFFICE.

EDMUND O. SCHWEITZER AND ALFRED HERZ, OF CHICAGO, ILLINOIS.

FUSE DEVICE.

1,270,335.

Specification of Letters Patent. Patented June 25, 1918.

Application filed December 17, 1914. Serial No. 877,697.

To all whom it may concern:
Be it known that we, EDMUND O. SCHWEITZER and ALFRED HERZ, citizens of the United States, residing at Chicago, in the county of Cook and State of Illinois, have invented a certain new and useful Improvement in Fuse Devices, of which the following is a full, clear, concise, and exact description, reference being had to the accompanying drawings, forming a part of this specification.

Our invention relates to improvements in fuse devices and more particularly to those of the character indicated in our copending application, Serial No. 824,412, filed March 15, 1914.

One object of our invention is to provide a fuse support with a fusible link confined between two blocks under pressure, the channel between said blocks having one or more sharp reverse bends formed by what may be termed "baffle plates" on said blocks which aid in extinguishing the arc that tends to form when the fuse blows.

Another object is to provide an improved fuse link having bends therein near the point where it is intended to fuse whereby the effect of a magnetic blow-out is obtained to a certain extent.

A further object is to provide a way of protecting fuse links against corrosion and consequent change of rating from reduction of cross sectional area due to this action.

Other objects are to provide certain structural refinements which will be apparent without specific enumeration.

In the accompanying drawings, we have illustrated one embodiment of the invention.

Figure 1 is a sectional elevation on the line 1—1 of Fig. 2.

Fig. 2 is a bottom plan view.

Fig. 3 is a bottom plan view of the upper one of the two blocks between which the fuse is confined.

Fig. 4 is a top plan view of the lower one of said blocks.

Fig. 5 is a perspective view of the fuse link.

Fig. 6 is a central sectional elevation of a modified form of link.

Fig. 7 is a bottom plan view of a modified form of terminal.

Fig. 8 is a section thereof on the line 8—8 of Fig. 7.

Fig. 9 is a view of a detail of construction.

55

The device consists of a socket member 1 and a plug member 2 which latter is provided with a handle 3 whereby it may be removed from or inserted into the socket member at will. The socket member is intended to be secured to a fixed support by means of screws passing through the apertures 4—4.

The removable plug member carries on its upper side a block 5 of insulating material, porcelain for example. Said block has cemented or otherwise secured to its lower side, a plurality of smaller blocks 6, 7 and 8 which match with an additional pair of blocks 9—10 similarly secured to the main body portion 2 of the plug member. The blocks 6, 7, 8, 9 and 10 may be made of limestone or silica, the upper and lower sets of blocks forming in effect, upper and lower compression blocks between which the fuse link 11 is confined. The meeting faces of said upper and lower blocks are so shaped as to provide, when spaced apart the thickness of the fuse link, a channel having a number of abrupt bends therein, portions of what may be termed the upper compression block, fitting into recesses in the lower compression block, and vice versa. These projecting portions may be termed baffle plates.

The blocks 2, 5, form compression members and the engaging limestone blocks 6, 8, 9, 10 form facing members for the compression members.

The fuse is compressed between the upper and lower compression blocks, the porcelain block 5 being drawn downwardly by a pair of springs 12, the enlarged ends of which fit within suitable recesses 13 therein.

The plug member 2, exclusive of the shield 21 and handle 3 comprises a prismatic block generally parallelogrammatic in outline, of greater length from end to end than from side to side. The distance from end to end is governed by the length of the fuse required. The ends of the block are relatively narrow being only wide enough to provide proper terminals for the fuse 11. The fuse 11 extends from end to end over the top of the block 2 in a substantially straight run. The sides of the block are cut away at opposite extremities as shown in dotted lines in

Fig. 4 and in full lines in Fig. 1 to provide lodgment for the clips 30. The clips 30 are made of metal. The body of the clips is fastened against the side wall of the adjacent recess as by means of screws or pins 31. Suitable ears 14, 15 forming terminals for the fuse 11 are bent over the adjacent ends of the block 2. The fuse 11 is clamped to these terminals 14, 15 by means of the screws 16, 17. Ears 18, 19 extend diagonally from the clips 30 at the adjacent corner of the block 2. These ears form switch blades adapted to coöperate with the stationary terminals or contacts hereinafter described. The plug member fits within the socket member preferably somewhat diagonally with respect to the latter, the general coöperation of parts in this regard being substantially the same as in our copending application 20 above identified.

The fuse link 11 is narrower at its middle portion than elsewhere in order to insure that it will melt at this point. The narrow portion is bent back and forth between the 25 baffle plates. The magnetic field set up adjacent these bends is therefore so disposed with respect to the bends themselves as to aid in extinguishing the arc which tends to form, thus providing, to a certain extent, a 30 magnetic blow-out.

When the fuse blows, the upper and lower compression blocks are brought together, thereby tending to extinguish immediately the arc which would otherwise form, this 35 tendency being aided by the magnetic blow-out. The baffle plates aid in eliminating the arc by interposing barriers across the path which the arc would have to follow. These barriers, therefore, insure against the formation of an arc thereby increasing the efficiency of the device. After the fuse blows, the plug member may be withdrawn and the blown fuse replaced by a new fuse. This 40 renewal is facilitated by the fact that the block 5 may be readily released from the springs 12, thus permitting the separation of the upper and lower compression blocks. The fuse link may have its ends coated with 45 easily puncturable lacquer 20 or other suitable material (see Fig. 5) which chips off easily when the ends of the link are being fastened beneath the screw 16-17. The lacquers obtainable on the market give a coating which is generally insulating. The 50 insulation feature is accidental. The quality that is essential is that the coating shall be chemically inert to the corrosion gases present in the atmosphere and shall offer protection against corrosion of the metal of the 55 fuse. The pressure causes the lacquer coating to chip off thereby exposing the metal and insuring good electrical contact. Since the lacquer does not chip off, however, except immediately adjacent to the screws, 60 the metal of the exposed part of the fuse

will not be corroded. This feature of preventing corrosion of the exposed parts of the fuse is of importance as it prevents any change in the capacity of the fuse. We have found that where an exposed fuse is 70 subject to corrosion the carrying capacity of the exposed portion is often so much changed as to change the rating of the fuse and also to cause the blowing of the fuse at the wrong point.

We consider that the above method of protecting the exposed part of the fuse constitutes an important part of our invention. We do not intend to be limited to the protection of fuses subject to compression as above 80 described, but intend the invention to apply to other forms of fuses where the terminals or any other parts are exposed. In Fig. 6 a modified form of fuse link is shown having its ends similarly coated.

It will be noted that the recesses in which the terminals 18 and 19 are located, are covered and protected by a flange 21 on the plug member. Said flange is more or less oval in outline but is extended at opposite 90 ends as shown more particularly in Figs. 2 and 4 so as to cover said recesses. This flange also forms a shield for the handle 3. While the plug as a whole, is arranged diagonally with respect to the block for the 95 purpose of economizing space, as shown in Fig. 2, the flange itself is arranged with its main axis more nearly parallel to the main axis of said socket member, and is so shaped as to avoid to a great extent, the appearance 100 of being diagonally arranged. With the arrangement provided, the ends of the fuse link do not pass the stationary contacts when the plug is being inserted or withdrawn.

In Figs. 7 and 8, we have shown a modified form of terminal which is loosely mounted within a suitable recess in the porcelain socket member whereby said terminals automatically adjust themselves to the 110 knife contacts, said contacts comprising a suitable block of conducting material 22 to which is secured by means of a screw 23, a folded-over strip of metal 24. The latter is loosely received within a slot 25 and is 115 locked against removal by the screw 23 which projects into a recess 26. The conductor 27 is received within an opening in the conducting block 21 and is secured by a set screw 28 in the manner illustrated in the 120 preceding figures.

In Fig. 9 a spring 12^a is shown with a wired guard 12^b, of such length that the guard will be stretched tight before the spring is fully expanded and thereby save 125 the spring from breakage. Such breakage might occur due to sudden expansion of the spring when the operator forces the enlarged ends thereof out of the recesses 13 in renewing the fuse strip.

It will be understood that changes and modifications may be made without departing from the spirit of the invention.

Having thus described our invention what we claim as new and desire to secure by Letters Patent of the United States is:

1. In a fuse device, a fuse, a pair of compression members lying upon opposite sides of the fuse, said members having a baffle member of refractory material at the central portion and having facing members for engaging opposite sides of the fuse, said facing members lying upon each side of the baffle member and comprising surfaces of refractory material for each of the compression members, and means for pressing the compression members toward each other so that the facing members press against opposite sides of the fuse.
2. In a fuse device, a plug member comprising an insulating body member and an outer insulating block member, a fuse having a reduced central portion lying between said members and having terminal portions extending beyond said members, a baffle of refractory material lying upon one of said members substantially centrally thereof, facings of refractory material secured upon the members and engaging opposite sides of the fuse on each side of the baffle member, and means for pressing the facings against the fuse.
3. In a fuse device, a pair of insulating blocks, resilient means drawing said blocks toward each other, a plurality of compression blocks secured to each of said first mentioned blocks, said compression blocks forming engaging facings for the insulating blocks for engaging and crushing the fuse when the same is softened by melting, said compression blocks having intermediate their ends projections and recesses inter-fitting with each other, a fuse having a central portion, said central portion passing over said projections and recesses and lying between said facing members and terminals for clamping the ends of the fuse.
4. A fuse device comprising a plug member and a socket member, the latter having a pair of recesses for circuit terminals, said plug member being arranged to fit diagonally within said socket member and having a flange with projections at opposite ends to cover said recesses, said flange being generally oval in outline with its main axis arranged more nearly parallel to the axis of the socket member than the rest of the plug member.
5. In a fuse device, compression blocks having portions thereof in the form of interfitting baffle plates, a fusible link having a reduced central portion adapted to be blown, said reduced portion lying between the compression blocks and being bent back and forth between the baffle plates, said fuse

having terminal portions extending out beyond the compression blocks, said terminal portions being of relatively greater capacity, and terminal members for clamping the terminal portions of the fuse.

70

6. A metal fuse link having terminal portions adapted to be clamped to suitable terminals, the portions adjacent the terminal portions being adapted to be exposed, said terminal portions and said adjacent portions being coated with a protective film over the metal of the fuse to preserve those parts from corrosion and to prevent changing of the capacity of the fuse.

75

7. In combination, a fusible metal link, means covering the central portion of the link, said means being adapted to prevent arcing when the fuse blows, said fusible link having exposed ends, said exposed ends comprising terminal portions and a film of insulating material covering the metal of the exposed part of the link to prevent corrosion and consequent change of capacity of the fuse, and terminals for clamping the terminal portions of the link, the action of clamping the terminal portion being adapted to break the film to expose the metal of the link under the terminal.

80

8. In combination, a fusible metal link, said link having a reduced cross section along its central portion to determine the location of blowing of the link, said link having exposed portions, said exposed portions comprising the terminal portions and a film of insulating material covering the metal of the exposed portions of the link to prevent the corrosion and so prevent changing the capacity of the fuse, and terminals for clamping the terminal portions of the links, the action of clamping the terminal portions being adapted to break the film to expose the metal of the link under the terminals.

95

9. The method of protecting the exposed ends of metallic fuses which consists in coating the exposed metallic end with a film of protective material to prevent corrosion and so prevent changing the capacity of the fuse, and then clamping the coated end in a suitable terminal with sufficient pressure to break the protective film under the clamping means and thus provide contact of the fuse to the terminals.

100

10. In a fuse device, a socket member and a plug member, coöoperating terminals on said members, the stationary terminals on said socket member being loosely received within recesses therein whereby they automatically adjust themselves to the contacts on said plug member.

105

11. In a fuse device the combination with the separable compression blocks and a fuse interposed between the same, of springs at the sides of the compression blocks for holding the same together and guards con-

110

115

120

125

130

sisting of strings 12^b for limiting the extent of movement on the part of the springs.

12. In a fuse device, a plug member comprising a prismatic block having side faces, 5 a fuse member extending from end to end over the top of said block, the ends of said block being relatively narrow and having substantially parallel faces, and metal clips secured to the side faces of the block adjacent the end faces of the block, each of said 10 clips having an ear extending over the adjacent end to form a fuse terminal, and each clip having an ear extending outwardly from the edge of the adjacent end to form a switch blade.

13. In a fuse device, a plug member comprising a prismatic block having side faces, 5 a fuse member extending from end to end

over the top of said block, the ends of said block being relatively narrow and having substantially parallel faces, and metal clips secured to the side faces of the block adjacent the end faces of the block, each of said clips having an ear extending over the adjacent end to form a fuse terminal, and each clip having an ear extending diagonally at the edge of the adjacent end to form a switch blade. 20

25 In witness whereof, we hereunto subscribe our names this 16th day of December, A. D. 30 1914.

EDMUND O. SCHWEITZER.
ALFRED HERZ.
